UNITED STATES PATENT OFFICE.

HARRY C. McCARTY, OF WILLIAMSPORT, PENNSYLVANIA.

JOURNAL-BOX LID.

SPECIFICATION forming part of Letters Patent No. 703,736, dated July 1, 1902.

Application filed August 30, 1901. Serial No. 73,771. (No model.)

To all whom it may concern:

Be it known that I, HARRY C. McCARTY, a citizen of the United States, residing at Williamsport, in the county of Lycoming, State 5 of Pennsylvania, have invented certain new and useful Improvements in Journal-Box Lids, of which the following is a specification.

This invention comprises certain improvements in car-axle boxes whereby the wear and 10 rattling between the lid and the box are largely prevented and the dust is prevented from entering the box through the opening over which the lid extends.

In the accompanying drawings, Figure 1 is 15 a longitudinal central section through a car-axle box, illustrating the improvements. Fig. 2 is a partial section on the line A A of Fig. 1. Fig. 3 is a front view of the box and lid; and Fig. 4 is a sectional view showing a bolt 20 for attaching the lid to the box, differing in form from that shown in Fig. 1.

Referring to Figs. 1 and 3 of the drawings, 1 indicates a car journal-box, which may be of any desired form, and 2 indicates the car-journal. Upon the outer face 3 of the box and extending along each side of the opening is arranged a rib 4. The box is formed with an upward projection 5, the outer face of which is flush with the face of the box, and 25 secured within an opening 6 in said projection is a bolt B. This bolt has a shank 7 extending through the opening, a shoulder 8, fitting against the outer face of the projection, and a head 9. The bolt may be secured by 30 any suitable means, such as the nut 10 and locking-pin 11. In the face of the projection 5 and surrounding the bolt is an annular concentric recess 12, which is adapted to receive 35 an annular rib 13 upon the inner face of the lid 14. Surrounding the bolt B is a sleeve 15, having a flange 16 at its outer end, and said sleeve and bolt extend through an opening 17, formed in the lid concentric with the rib 13. The sleeve is held in position by the 40 head 9 of the bolt, and between the flanged head 16 of the sleeve and the lid is arranged a helical spring 18, surrounding the sleeve and tending to hold the lid against the face of the box. Upon the outer face of the lid 45 50 surrounding the spring is an annular projection 19 for retaining and centering the spring around the sleeve. The lower end of

the lid is preferably provided with a handle portion 20.

When the box is closed, the sides of the lid 55 fit closely between the ribs 4, as shown in Fig. 3, and the lid is held firmly against the face of the box by the pressure of the spring 18. When it is desired to open the box, the lid is pulled outward against the action of the 60 spring for a sufficient distance to clear the ribs 4, and it may then be swung laterally to open the box. These ribs, which fit along the edges of the lid, prevent dust and sand which are swept up by the train and beat 65 against the forward side of the box from entering. The annular rib 13, fitting within the recess 12, supports the lid and prevents it from vibrating, thus taking the wear off of the bolt and the walls of the opening in the 70 lid through which the bolt extends. In car journal-boxes wherein the lid is supported directly upon the bolt it is found that the bolt and the opening in the lid both wear, owing to the pounding of the wheels upon the track, 75 and that this wear decreases the efficiency of the lid as a means for excluding dust from the box and also results in rattling noises between the parts.

In Fig. 4 the flanged sleeve is dispensed 80 with and the bolt B is formed with an enlarged head 21, which extends over the end of the helical spring 18. The outer portion 22 of the bolt, as shown, has a greater diameter than the inner portion, and the spring extends 85 between the head 21 and the lid, surrounding the part 22 and the annular projection 19, said parts serving to center the spring at both ends.

Having described my invention, what I 90 claim, and desire to secure by Letters Patent, is—

1. The combination with a car journal-box having an opening in its forward end, ribs at the sides of said opening; and a projecting 95 bolt above said opening, there being an annular recess or socket surrounding said bolt, of a lid pivotally mounted upon the bolt and adapted to fit between said ribs, said lid having a projection fitting into said recess, and a spring surrounding the bolt and bearing 100 against the lid.

2. The combination with a car journal-box having an opening in its forward end, ribs at

the sides of said opening, and a projecting bolt above said opening, there being an annular recess or socket surrounding said bolt, of a lid pivotally mounted upon the bolt and adapted to fit between said ribs, said lid having an annular projection fitting into said recess, and a spring surrounding the bolt and bearing against the lid.

3. The combination with a car journal-box having an opening in its forward end, ribs at the sides of said opening, and a projecting bolt above said opening, there being an annular recess or socket surrounding the bolt,

of a lid pivotally mounted upon said bolt and adapted to fit between the ribs, and having 15 an annular projection fitting into said recess, a flanged sleeve upon the bolt, and a spring interposed between the lid and the flange upon the sleeve.

In testimony whereof I affix my signature 20 in presence of two witnesses.

HARRY C. McCARTY.
